UNITED STATES PATENT OFFICE.

THEODULE ROBIN, OF HYDE PARK, ASSIGNOR, BY MESNE ASSIGNMENTS, TO HIMSELF AND JAMES A. MAILLOUX, OF BOSTON, MASSACHUSETTS.

WATCH-CASE PENDANT AND BOW.

SPECIFICATION forming part of Letters Patent No. 340,366, dated April 20, 1886.

Application filed November 30, 1885. Serial No. 184,259. (No model.)

To all whom it may concern:

Be it known that I, THEODULE ROBIN, of Hyde Park, in the county of Norfolk, of the Commonwealth of Massachusetts, have invented a new and useful Improvement in Connecting Pendant-Bows to Watch-Case Stems or other Articles of Like Character; and I do hereby declare the same to be described in the following specification, and represented in the accompanying drawings, of which—

Figure 1 is a side view, partly in section, of a watch-case stem and pendant-bow having my improvement, the nature of which is defined in the claim hereinafter presented. Fig. 15 2 is a side view of the pendant-bow.

The object of the invention is to prevent the pendant-bow from becoming accidentally detached from its carrier or the stem of a watch, such pendant-bow being capable of 20 being turned laterally in such carrier or stem.

In carrying out my invention I screw-thread the pendant-bow in the parts thereof that are to enter the holes in the stem, one screw formed in one of such parts being a "right threaded" 25 one, and the other being a "left threaded" one, the holes being correspondingly screw-grooved to receive such screws. Before the stem is brazed or soldered to the watch-case, the ends of the bow are to be inserted in the 30 holes of the stem and the stem is to be revolved

within the bow in a manner to cause the screws of the bow to engage with and be drawn into the screw-grooves of such holes, all being as shown in Fig. 1, in which—

A is the pendant-bow, B the watch-stem, 35 C the case, and D the headed spindle that extends within the stem, and serves to aid in effecting the winding of the watch. The screws on the pendant-bow are shown at *a a* and the screw-holes at *b b*, the spindle extending 40 between them when they are in the stem.

From the above it will be seen that after the stem is fixed to the case of the watch the pendant-bow, though capable of being turned in the stem laterally thereof, as usual, cannot be unscrewed therefrom or accidentally drawn out of engagement therewith. 45

I claim—

The pendant-bow provided with a right-threaded screw on one of the parts to enter 50 the stem, and a left-threaded screw on the other of such parts, in combination with the carrier or stem having its pendant-receiving holes screw-grooved to engage with such right and left threaded screws, all being substantially as set forth. 55

THEODULE ROBIN.
